US00D535861S

(12) **United States Design Patent** (10) **Patent No.:** **US D535,861 S**
(45) **Date of Patent:** **** Jan. 30, 2007**

(54) **POWERED NAILER TOOL**

(75) Inventor: **Colin Snowball**, Pocklington (GB)

(73) Assignee: **GMCA Pty Ltd**, Victoria (AU)

(**) Term: **14 Years**

(21) Appl. No.: **29/257,986**

(22) Filed: **Apr. 13, 2006**

(30) **Foreign Application Priority Data**

Feb. 22, 2006 (EM) 000485677

(51) **LOC (8) Cl.** **08-05**

(52) **U.S. Cl.** **D8/69**

(58) **Field of Classification Search** ..... D8/14.1, D8/61, 62, 63, 64, 65, 66, 67, 68, 69, 70; 81/57.11, 429, 464, 465, 466, 469, 489; 173/13, 173/104, 114, 168, 169, 170, 171, 178, 201, 173/211, 213, 217; 408/20, 124, 125, 234, 408/241 R; 451/358; 310/50; 227/8, 113, 227/114, 120, 130, 136, 142

(57) **CLAIM**

The ornamental design for a powered nailer tool, as shown and described.

DESCRIPTION

FIG. 1 is a top view of the powered nailer tool of the present invention;

FIG. 2 is a bottom view of the powered nailer tool of the present invention;

FIG. 3 is a front view of the powered nailer tool of the present invention;

FIG. 4 is a rear view of the powered nailer tool of the present invention;

FIG. 5 is a left view of the powered nailer tool of the present invention;

FIG. 6 is a right view of the powered nailer tool of the present invention;

FIG. 7 is a right perceptive view of the powered nailer tool of the present invention; and,

FIG. 8 is a left perceptive view of the powered nailer tool of the present invention.

1 Claim, 6 Drawing Sheets

FIG. 2

FIG. 1

FIG. 4

FIG. 3

FIG. 5

FIG. 6

FIG. 7

FIG. 8
